UNITED STATES PATENT OFFICE.

LEWIS CHAEM ZWERDLING AND SAMUEL A. GREEN, OF BROOKLYN, NEW YORK.

LIFE-SAVING DEVICE.

1,002,109.

Specification of Letters Patent. Patented Aug. 29, 1911.

Application filed October 2, 1909. Serial No. 520,745.

To all whom it may concern:

Be it known that we, LEWIS CHAEM ZWERDLING and SAMUEL A. GREEN, citizens of the United States, residing at Brooklyn, in the county of Kings and State of New York, have invented certain new and useful Improvements in Life-Saving Devices, of which the following is a specification.

This invention relates to improvements in life saving devices and relates particularly to the construction of a device the passenger car of which will be non-turning in water and which will be effectively ventilated.

One of the objects of the invention is the construction of a submarine life saving boat or device having a passenger car adapted to be held by force of gravity in a position holding the passengers vertical.

Another object of the invention is the construction of a submarine boat having a ventilating tube adapted to allow air and to prevent water entering the interior of the boat and adapted to occupy a normal upright or substantially vertical position.

With the above and other objects in view the invention embraces certain combinations, constructions and arrangements of parts, clearly described in the following specification and clearly illustrated in the accompanying drawings, in which,

Figure 1 is a top plan view of the improved device. Fig. 2 is a side elevation thereof, Fig. 2^a is a detail perspective view of the rudder, Fig. 3 is a transverse sectional view of the ventilating tube, taken on the line 3—3 of Fig. 2. Fig. 4 is a side elevation of the rudder mechanism. Fig. 5 is a detail longitudinal sectional view of the boat, Fig. 6 is a detail elevation of the bow of the boat, Fig. 7 is a transverse sectional view of the boat. Fig. 8 is a detail of the propeller-operating mechanism and, Fig. 9 is an end elevation of the stern of the boat.

Referring to the accompanying drawings illustrating the construction of the improved life saving boat, 1 denotes the outer shell of the boat, which is preferably formed cylindrical and provided with tapering outer ends 2 and 3. The middle body portion of the cylindrical shell is provided with observing and light openings which are water sealed by glass disks 4. The shell 1 is further provided with trap doors 5, which hold the openings over the steps 6 normally closed and said doors are properly water sealed. Hooks 7 are located on the outer

side of the shell 1 so that the boat can be lowered from a vessel or landing.

The forward end of the boat is provided with a cone-shaped nose or spreader 8, which is connected thereto by a band 9, which encircles the end 2 so as to allow the nose of the water spreader to rotate thereon. The water spreader serves to cut the water in advance of the boat, so that the boat can move more easily through the same and the agitated water will not interfere with the sight line, or the light, which passes through the transparent forward end of the boat. A wire cage 10, having glass sections 11 is connected to the boat 1. This cage completely covers the front end of the boat 1. The inner end of the rod 12 is suitably supported by braces or other mechanical supports arranged in the boat 1. The outer end of the nose 8 is supported by a rod 12, which is in turn partly supported by the wire cage 10. The rear end 3 is provided with a circular wall 13, which is water sealed on the end 3 by a circular guide 14, which is provided with a packing 15. The lower end 16 of a ventilating tube 17 extends through a water sealed opening in the wall 13 and said lower end is flared outwardly and located within the passenger car 18, which is adapted to ride on the inner side of the boat shell wall. The upper end of the ventilating tube 17 is disposed at right angles to the lower end so that said upper end can be held above the water line, and for this purpose said upper end is made considerably higher than the boat. On the top of the upper end of the tube 17 a hood 19 is mounted, said hood being provided with a right angular inner end 20, which is slightly deflected toward the tube 17. On the tube 17 is an auxiliary hood 21 having an outwardly deflected angular portion 22, which is spaced above the inwardly deflected angular portion 20 of the outer hood 19, so as to leave a space for the passage of air therebetween. The angular portion 20 of the hood 19 is provided with openings 23, whereby the water thrown into the hood 19 can escape therefrom. Air enters the tube 17 through the passage between the angular portions 20 and 22 and passes downward into the lower end of the tube and thence into the interior of the car 18, thus supplying any passengers therein with fresh air. On the tube 17 is suspended a bearing bracket 24, on which is journaled a pro-

peller shaft 25, which shaft carries a beveled gear 26 and a paddle wheel or other propeller 27. The gear 26 engages with a drive gear 28 on a shaft 29 which extends inwardly of the car 18, and said shaft 29 is provided on its inner end with a wheel 30, having a handle 31 thereon, whereby the propeller can be operated by hand, or if desired by motive power. The tube 17 also supports a depending bearing bracket 32, which is provided with a bowed lower end 33. The bowed end 33 supports a rudder 34, which is movably connected thereto by an eye 35. The rudder 34 is operated by means of rods 36 and 37, the outer ends of which are bent. The outer end of the rod 36 is bent at right angles to itself and the outer end of the rod 37 is bent rearwardly toward itself. This last end is passed through an eye 38 on the end of the rudder 34 adjacent the end 3, and is provided with a head 39, whereby said end will not become disconnected from the rudder 34. The rod 36 is connected to the wall 13 and forms a pivot for the rudder 34 and the rod 37 extends inwardly of the boat and is provided on its inner end with an operating crank 40, which is mounted for operation near the wheel 30 but so as not to interfere with said wheel 30. When the crank 40 occupies the position shown in Fig. 6 the rudder will be held on plane parallel with the longitudinal axis of the boat.

The car 18 is movably supported on the interior of the shell 1 so that when the boat is rotated by the waves or water the car will be held so that the passengers will be normally substantially vertical. For this purpose the car is provided with wheels or runners 41, which are pivotally supported on the outer side thereof and which are adapted to ride on angular tracks 42, fixed on the inner side of the wall of the shell 1, and of a circular shape. The car 18 is provided with cushioned seats 43, for the comfort of the passengers.

The shaft 29 is divided at 44 and the ends thereof are provided with engaging gears 45 and 46, whereby the speed of the shaft end connected to the operating wheel will be increased, and the propeller will be driven at a higher rate of speed than the rate of speed of the wheel 30. Two propellers may be arranged on the boat as shown in Fig. 8, in this figure the beveled gear 26 is mounted on a shaft 47 having two propellers 48 arranged thereon, which would be driven in a common direction by the rotation of the drive shaft 29.

When the passengers are seated in the car 18 they will not be in danger of being drowned by the water surrounding the boat nor in danger of being seriously tossed

about by the waves. Should it be desired to hold the car 18 against movement of the shell 1 the hooks 49 of the said shell are connected to screw eyelets 50.

Having described our invention we claim:

1. In a life saving device, the combination with a shell, of means for supporting passengers in vertical positions within the shell, a transparent end for the shell, a rod extending through the end, a water spreader journaled on the shell and the rod and means for propelling the shell.

2. In a life saving device, the combination with a shell of tracks secured to the inner wall thereof, a car having wheels engaging the tracks adapted to rotate freely on said tracks, an end wall for the shell adapted to rotate thereon, an annular packing device adapted to water seal the connection between the end wall and the shell, a ventilating tube connected with the interior of the shell and ear projecting through the end wall and above the shell, a hood for the ventilating tube having its lower portion provided with an upwardly turned flange having its edge inwardly deflected, a member in the hood comprising a flange depending over the hood flanged portion and outwardly deflected over said portion to form a passage for air therebetween, a support secured to the lower part of the ventilating tube, a rudder having slidable connection with the support, a pivot securing the rudder to the end wall, and an angular operating rod having sliding connection with the rudder extending within the shell.

3. In a life saving device, the combination with a shell, of means for supporting passengers within the shell, a ventilating tube for the shell, an end wall rotatably connecting the tube to the shell, a U-shaped support depending from the ventilating tube, a rudder having slidable connection with the U-shaped support, a pivot connecting the rudder to the end wall, an operating rod having its outer end bent to engage the rudder and a strap adapted to connect the outer end of the rod slidably to the rudder.

4. In a life saving device, a shell adapted to contain passengers, a shaft extending from the front end of the shell, a band rotatable on the shell, and a water spreader connected at its front end to the shaft and at its rear end to the band.

In testimony whereof we affix our signatures, in presence of two witnesses:
